UNITED STATES PATENT OFFICE

1,974,402

HEAT EXCHANGER

John O. Templeton, Pittsburgh, Pa.

Application January 31, 1931, Serial No. 512,585

Renewed March 29, 1933

9 Claims. (Cl. 257—183)

The present invention relates broadly to the art of heat exchanging, and more particularly to heat exchanging as between two liquid bodies such for example, as milk.

5 It is customary in the art to which the present invention relates to subject milk to a heating or sterilizing operation at a temperature calculated to destroy objectionable bacteria. The present invention contemplates utilizing a heat exchanger in connection with such an operation for the purpose of effecting a regenerative cycle by transferring the heat of the treated milk to the body of milk passing to the heater. Such a heat exchanging operation not only conserves heat in 10 the sterilizing operation by decreasing the range through which it is necessary to rise the temperature of the milk, but also effects a heat extraction from the previously heated milk, thereby facilitating subsequent handling operations of the 15 treated milk.

It is customary to effect a sterilizing operation of the character hereinbefore referred to at a temperature in the neighborhood of 160° F. so that in many cases it is necessary to cool the 20 sterilized liquid before bottling the same.

While the broad idea of a regenerative cycle of the general nature herein contemplated for purposes of heat abstraction, aeration and the like, is not new, apparatus as heretofore provided for this purpose has presented certain difficulties with respect to changes in the volume of liquid being treated and in the cleaning of the apparatus after use. In most of the States, legislation has been enacted requiring dairies and the 30 like to effect a thorough cleaning of the apparatus into contact with which the milk is brought after each use thereof. Where tubes are utilized for the carrying of milk, it becomes apparent that the problem of efficiently cleaning the tubes and 35 the tube headers is a serious one. In addition to this, apparatus with which I am familiar has been designed with respect to the handling of a predetermined and substantially constant volume of liquid.

40 The present invention contemplates an improved construction involving a series of tube nests, which tube nests each include headers at the opposite ends of the tubes, the headers for the tube nests being detachably coupled together. 45 Due to this construction the headers may be readily separated for cleaning and for the purpose of permitting the insertion or removal of one or more headers for increasing or decreasing the total capacity of the unit. These individual tube 50 nests may be referred to as units, each including

a predetermined number of tubes through which there is a flow in series from the inlet of the tube pass to the discharge thereof, the assembling of a plurality of units automatically affording a flow in parallel through the various units.

It is a further object of the present invention to provide a plurality of units of the general character referred to which may be compactly assembled whereby the apparatus as a whole will occupy a comparatively small space which may be located as closely as convenient to the sterilizing apparatus in order to facilitate the handling of the milk and in order to permit the milk passing to the sterilizer to receive the full benefit of the heat from the previously sterilized milk.

Still another object of the present invention is to provide an apparatus of the character described which is of such construction that assembly and disassembly may be readily accomplished, and in which the individual units are of such size that they may be readily placed in a suitable cabinet for purposes of sterilization before further use.

In the accompanying drawings I have shown for purposes of illustration only, a preferred embodiment of the present invention. In the drawings:

Figure 1 is a perspective view of a portion of an apparatus constructed in accordance with the present invention;

Figure 2 is a longitudinal transverse sectional view through a structure built in accordance with the showing of Figure 1;

Figure 3 is a partial longitudinal sectional view along the line III—III of Figure 2, looking in the direction of the arrows;

Figure 4 is a view, partly broken away, along the line IV—IV of Figure 2, looking in the direction of the arrows;

Figure 5 is a side elevational view of one of the return headers; and

Figure 6 is a side elevational view of one of the gaskets utilized intermediate the return headers.

In Figure 1 of the drawings there is illustrated a heat exchanging apparatus of the general character herein contemplated including three units of tube nests designated A, B and C respectively. The unit A includes an inlet header 2 and a return header 3 between which extend tubes 4 in vertically superimposed relationship. The intermediate unit likewise includes an inlet header 5, a return header 6 and tubes 7, while the third unit, of similar construction, includes an inlet header 8, a return header 9 and tubes 10.

By reference to the drawings it will be noted

110

that each of the inlet headers 2, 5 and 8 is of the same construction, and therefore interchangeable one with the other. Each inlet header is formed adjacent the lower end thereof with a transversely extending opening 11, which openings constitute a continuation, one of the other, when the headers are in assembled relationship as illustrated in Figure 1. These openings therefore provide an inlet manifold from which extend the bottom tubes of the nests 4, 7 and 10 respectively, effective for conveying liquid received from the manifold in the direction indicated by the arrows 12. This liquid is conveyed into transversely extending openings 14 in the lower ends 10 of the return headers 3, 6 and 9.

These openings are effective for returning the liquid in the direction indicated by the arrows 15 through the second row of tubes of the respective headers. This liquid in turn enters openings 16 20 in the inlet headers 2, 5 and 8, similar in all respects to the openings 14 and effective for again returning the liquid to the return headers 3, 6 and 9, respectively, through the tubes of the respective nests. More particularly from Figure 2 of the drawings it will be apparent that this operation is repeated through successive openings 17 25 in the return headers 3, 6 and 9 and successive openings 18 in the inlet headers 2, 5 and 8 until the top row of tubes is reached. These tubes discharge into transversely extending openings 19 in the inlet headers 2, 5 and 8, which openings, similar to the openings 11, are adapted to align one with the other when the units are assembled and provide a discharge manifold.

30 It will be observed that the openings 11, 16, 18 and 19 in the inlet headers extend the entire width of the respective headers and open through the sides 20 thereof. In order to prevent the openings 16 and 18 from constituting cross connections intermediate the inlet manifold 11 and the outlet manifold 19, and further to provide a tight joint intermediate the respective headers, there are provided gaskets 21, which gaskets are perforated in alignment with the openings 11 and 19 and solid 35 throughout the remainder of their length. They thus constitute division means between the headers, isolating the headers in such manner that there can be a flow in parallel through the tube nests of all of the units as a whole with a flow in series through the tubes of any one nest or unit. In like manner there are provided gaskets 22 intermediate the return headers 3, 6 and 9 which are similarly perforated adjacent the transverse opening 14 only and solid throughout the remainder of their length to insure an operation of the character referred to.

35 For effecting the delivery of a liquid into the manifold 11, there is provided a side plate 23 serving as a closure for one side of the apparatus and serving to clamp a sealing gasket 24 in position against the outside of the inlet header 2. Cooperating with the side plate 23 is an inlet connection 25 through which fluid is supplied to the manifold.

40 45 50 55 60 65 70 75 Cooperating with the outside of the inlet header 8 is a side plate 26 which is effective through the medium of a gasket 27 for sealing the outer ends of all of the transverse openings within the inlet headers. It will be understood that the gasket 24 is only perforated adjacent its lower end in line with the transverse openings 11. The gasket 27 is likewise perforated adjacent its upper end only for cooperation with the outlet openings 19 to permit the discharge of fluid therefrom through the gasket into an outlet connection 28 similar to

the inlet connection 25. Extending transversely through the inlet headers at suitably spaced points are through bolts 29. The lower bolt is effective for clamping the inlet headers together and for securing the inlet connection 25 in place, while the upper bolt 29 is likewise effective for exerting a clamping action and securing the outlet connection 28 in place. It is to be understood that the gaskets are all formed with openings so located as to permit the passage therethrough of clamping and assembly bolts 29.

80 By reference more particularly to Figure 3 of the drawings, it will be observed that the inlet headers 2, 5 and 8 are of such configuration in horizontal transverse section as to form a parallelogram including no right angles. In the specific construction shown the individual headers are of rhomboidal shape and cross section, although it will be understood that they might be of equilateral dimensions on the respective sides so as to form rhombs, or of such other cross sectional area as to permit the attainment of the object now to be pointed out.

85 90 95 100 105 110 115 120 125 130 135 140 145 150 By reference to Figure 2 it will be noted that the tubes 4, 7 and 10 are secured in position in openings 30 in the sides 31 of the respective inlet headers. The sides adjoining the tube plates 31 thus provided, extend at an angle thereto such that an axis 32 of one of the tubes when extended will project through one of the transverse openings in the inlet header and be freely accessible upon disassembly of the units for the reception of a brush, tube cleaner or the like. While the return headers 3, 6 and 9 may be of a construction similar to that just described, they are herein shown, for purposes of illustration only, as being rectangular in cross section.

125 130 135 140 145 150 The intermediate header 6 is illustrated as having the openings 14 and 17 extending entirely through the sides thereof, while the headers 3 and 9 are shown as having solid outer sides 33. Each of the headers 3, 6 and 9, however, is provided with a detachable closure plate 34, secured in place in any desired manner, and readily removable to permit cleaning of the tubes. For this purpose, the rear walls of the headers themselves are formed with openings 35 through which access to the tubes upon removal of the plates, is permitted. The return headers 3, 6 and 9, similarly to the inlet headers 2, 5 and 8, are adapted to be held in place by through bolts 36 which clamp the headers in cooperative relation about the gaskets provided intermediate the headers.

crease in pressure in the tubes such that in case of leakage, the tendency will be for the treated milk exteriorly of the tubes to again enter the tubes and thus pass again to the sterilizer. In this way 5 any contamination of the sterilized milk is prevented. The sterilized and heated milk in passing downwardly over the tubes transfers its heat to the milk within the tubes on its way to the sterilizer, thus cooling the sterilized milk, and 10 heating the incoming milk to a temperature such that the work of the sterilizer is correspondingly decreased.

Due to the particular cross sectional configuration of the inlet headers 2, 5 and 8, there is a 15 tendency for the same to slip one upon the other during the tightening of the through bolts 29. To obviate this slipping tendency, the headers may be provided with lugs or offsets 39 of suitable construction adapted to overlie an adjacent 20 header and prevent undesirable movement of the character referred to and more effectively interlock the inlet headers and the units when assembled.

Under normal conditions of operation the temperature of the sterilized milk, if delivered to the 25 heat exchanger at a temperature in the neighborhood of 160° from the sterilizer, may have its temperature reduced to approximately 70°. At this temperature the milk cannot be bottled and 30 it is necessary to subject the same to artificial cooling. For this purpose the milk may be either collected and passed through a cooler, or the heat exchanger may be assembled in cooperative 35 relation to a suitable cooler whereby the milk after leaving the outside of the bottom row of tubes of the regenerator will pass directly over the tube surfaces of a suitable cooling apparatus. Where such an operation is contemplated, I will 40 preferably supply the units of the heat exchanger with false tubes 40 effective for bridging the space between the heat exchanger and the cooler and continuing the path of flow of the milk. Such 45 a false tube is indicated in Figure 1. It will be understood that such false tubes do not communicate with the interior of the other tubes and constitute flow conducting means only as to their outer surfaces.

It will further be understood that the distributing troughs 37 for the heat exchangers may 50 either receive the milk through suitable connections directly from the sterilizer, or that they may be projected into the headers themselves and receive milk through suitable manifold openings 55 therein. The particular construction in this respect may be varied to suit the convenience of the user and does not limit the utility of the invention.

The advantages of the present invention arise 60 from a flexible, easily cleaned unit construction of the character described, whereby the capacity may be easily varied at will, and the parts readily disassembled and cleaned for sterilizing purposes.

While I have herein illustrated and described a 65 preferred embodiment of the present invention, it will be understood that changes in the construction and arrangement of the parts may be made without departing either from the spirit 70 of the invention or the scope of my broader claims.

I claim:

1. In a heat exchanger, a plurality of units 75 each including a tube nest, and individual headers for each nest at each end of the tubes, the headers at one end of the units forming substan-

tially in transverse section a parallelogram not including any right angles.

2. In a heat exchanger, a plurality of units each including a tube nest, individual headers for each nest at each end of the tubes, some of said headers having sides inclined to the axes of the tubes and permitting access to the tubes upon separation of the headers, and means for holding the headers in assembled relationship. 80

3. In a heat exchanger, a plurality of units each including a tube nest, individual headers for each nest at each end of the tubes the headers at one end of the unit having ports therein registering with the ports of the adjacent headers, the headers being arranged in face-to-face relation, means for detachably assembling the units, removable cleaning plates carried by certain of said headers, and inlet and outlet connections secured to other of said headers. 85

4. In a heat exchanger, a plurality of units each including a tube nest, individual headers for each tube nest at each end of the tubes, the headers at one end of the tubes being of rhomboidal cross section and the headers at the opposite end of the tubes being of rectangular cross 90 section. 95

6. In a heat exchanger, a unit comprising a header having transverse passages therethrough, tube receiving openings substantially normal to the axes of said passages, tubes in said openings, a second header cooperating with the opposite 100 end of said tubes and having tube receiving openings therefor, there being transverse openings in said second header substantially normal to the axes of said tubes. 105

6. In a heat exchanger, a unit comprising a header having transverse passages therethrough, tube receiving openings substantially normal to the axes of said passages, tubes in said openings, a second header cooperating with the opposite 110 end of said tubes and having tube receiving openings therefor, there being transverse openings in said second header substantially normal to the axes of said tubes, the side walls of one of said headers extending in a plane oblique to the axes 115 of the tubes. 120

7. In a heat exchanger, a plurality of units each including a tube nest, individual headers for each nest at each end of the tubes, some of said headers having sides inclined to the axes of the tubes and permitting access to the tubes upon separation of the headers, the headers at one end of the units having ports therein registering with the ports of the adjacent headers, the headers being arranged in face to face relation, and means for detachably connecting the individual 125 headers. 130

8. In a heat exchanger, a plurality of units each including a tube nest, individual headers for each nest at each end of the tubes, some of said headers having sides inclined to the axes of the tubes and permitting access to the tubes upon separation of the headers, means within the headers to insure a series flow through the tubes of each unit and a parallel flow through the 135 units as such, and means for detachably connecting the individual headers. 140

9. In a heat exchanger, a plurality of units each including a tube nest, individual headers for each nest at each end of the tubes, some of said headers having sides inclined to the axes of the tubes, and means within the headers to insure a series flow through the tubes of each unit and a parallel flow through the units as such. 145
